LIGATOR

Hans Albert Roeder, Berlin, Germany

Application May 20, 1932, Serial No. 612,599
In Germany May 23, 1931

1 Claim. (Cl. 128—326)

In tying up arteries and tissues during operations or bringing together the lips of a wound when stitching the practice has hitherto been to place a gut filament around the artery clipped with clamp forceps or around the tissue parts and to loop it to a surgical knot, and, when stitching wounds, to draw a gut filament or the like by means of a needle through the lips of the wound, to bring the lips together and then to knot the gut.

Appliances have also already been proposed for facilitating the forming of the knot. These appliances have, however, not been generally adopted in practice, as they are not only complicated but are difficult to manipulate. In addition the second loop required for making the knot has had to be formed with the fingers.

According to the invention the gut is prepared for tying up or stitching by a preliminary knot being formed in it. The loop need then only be drawn tight for tying up an artery or for bringing the lips of a wound together.

For manipulating the gut the invention provides an appliance, the object of which is to bring the loop to the desired place.

The appliance forming the subject matter of the invention is therefore an instrument into which a prepared gut filament having a loop is inserted.

A constructional example of the instrument according to the invention is illustrated in the accompanying drawings in which

Fig. 1 shows diagrammatically a surgical filament with a slip knot according to the invention.

Figs. 2 and 3 show a similar knot to that of Fig. 1, diagrammatically and in perspective,

Fig. 4 is a diagrammatic view of another way of forming the slip knot,

Fig. 5 is a similar knot to that of Fig. 4,

Fig. 6 shows another way of forming the slip knot,

Fig. 7 is a slip knot according to Fig. 2 shown diagrammatically, formed on a separate surgical filament,

Fig. 8 is the slip knot according to Fig. 7 shown in perspective,

Fig. 9 shows a gut according to Fig. 1, which is looped around a pin, and how a needle may be introduced through the hollow pin,

Fig. 10 shows in elevation a constructional form of an instrument for carrying out the invention having rigid finger rings,

Fig. 11 a constructional form with slideable finger rings,

Fig. 12 is a section on line XII—XII of Fig. 11,

Fig. 13 a somewhat modified form partly broken away,

Fig. 14 a side view of the upper part of Fig. 10 and

Fig. 15 another form of the instrument to an enlarged scale.

The forming of a loop by means of a knot which is made with one end of the filament on the middle part thereof is illustrated in Figs. 1 to 6. One end of the surgical filament bears the reference numeral 1 and the other end the numeral 2. 3 is the loop itself. It is made smaller by pulling the end 1 in the direction of the arrow A when the slip knot 4 is held fast.

Fig. 2 shows another way of forming the slip knot. The loop 3 is in this case also contracted by pulling the end 1. 5 is the part of the filament wrapped around the middle part thereof.

Fig. 3 shows the knot illustrated diagrammatically in Fig. 2 drawn together. It is not possible to enlarge the loop by pulling in the direction of the arrow B.

In the case of the filament shown in Fig. 4 the knot is tightened by nipping the passed-through end after the loop has been drawn tight.

According to Fig. 6, on the loop being pulled, the individual parts of the knot are laid tightly one on the other and the outer filament end is nipped.

The forms of knot illustrated are only given by way of example. It is not essential that the knot shall be formed as described above and other forms of knot may be used, as the gut swells owing to the moisture of the body, causing the knot to tighten up on the middle part of the filament, thus tying off the artery, as experiments have proved.

According to Fig. 7 a slip knot, as shown in Fig. 2, is formed on a gut filament 6 having a loop 7. Through the helical part of the knot a 40 second surgical filament 8 is inserted, so that the slip knot formed by the filament 6 is slideable on the filament 8. On a needle being threaded on to the filament 8 and the filament, after a portion of tissue or two lips of a wound which are to be drawn together have been pierced, being knotted with the loop 7, by pulling at the filament 8 in the direction C, the lips of the wound may be brought together and at the same time the loop formed by the filaments 7 and 8 may be contracted without any danger of the loop becoming loose again. Instead of forming a loop or eye 7 with the filament 6, it is of course also possible to knot the end of the filament 8.

which has been inserted in the needle with the free end of the filament 6.

From Fig. 8 it will be clearly seen how the filament 6 can be slid freely in both directions on the filament 8.

According to Fig. 9 a knot of the kind shown in Fig. 1 is wrapped around a tubular pin 9. The end 10 of the filament is threaded into a surgical needle 11. After the tissues have been pierced, 10 this end can be passed through the pin 9 in the direction of the arrow D. After the pin has been withdrawn from the slip knot the parts of the tissue are tied off in the manner described.

As shown in Fig. 10 the appliance for bringing the filament into position consists of a bar-shaped part 11' which is provided at one end with a somewhat thicker handle part and at the other end with a slightly tapered carrier part. The handle, 15 as shown in the drawings, is provided with rings 12, 13, 14 which are arranged in a known manner so that they can be grasped with the thumb and the first and second finger of the hand. The carrier part is tubular, has a channel 15 and is preferably bent over at an angle of 45° to the part 11' 20 as will be seen from Fig. 14. The free end 16 of the carrier part is ball-shaped, so as to avoid injury when the instrument is in use.

When the instrument is to be used, a gut filament 17 which is provided with a loop as described above, but which is not shown, is introduced at 16, so that it projects with the not illustrated loop at the other end of the channel 15 and the loop of the gut filament is passed over the handle of the clamp forceps which have been applied. With the instrument the loop of the gut filament is brought over the place to be tied off and drawn completely tight, the fingers of one hand gripping the rings 12, 13, and 14 and the other hand drawing the loop of the gut filament 40 tight.

As shown in Fig. 11 the rings for the middle and first finger may also be slidable on a non-circular, for instance a four-cornered, part 18 of the handle up to the point where they strike against the stop 19. In this extreme position they are held 45 by a leaf spring 20.

As shown in Fig. 11 the left-hand ring 12 may be pivoted on a pin 21 which is screwed into a guide part 22 which is slideable on the part 18. 50 The inner end of the ring part 12 is eccentric,

as will be seen from the figure, so that the gut filament 17 can be gripped between the right-hand ring 13 and the left-hand ring 12. The ring 12 is held in this position by a spring 23.

When a gut filament is introduced into the tubular part and is clamped between the rings 12 and 13, the loop of the filament is first reduced in size by moving the rings 12 and 13 in the direction of the arrow A, and on the pull continuing is drawn completely tight. After the 10 artery has been tied off the gut filament 17 is freed from the clamped position by swinging over the ring 12 in the direction of the arrow E.

The constructional form shown in Fig. 13 differs from that of Fig. 11 only in this, that the two 15 rings 12 and 13 are rigidly connected to the slideable part 22. The gut filament can in this case be twined round the rings. By moving the rings downwards the loop is contracted or drawn tight.

In the constructional form shown in Fig. 15 the ball-shaped part 16 is arranged to be slipped on to the free end of the part 11'. The bent over end 24 is not bored but has a groove 25. The gut filament 17 can therefore be threaded into the 25 ball-shaped part 16 and the connection between the instrument and the gut filament is effected by slipping the ball-shaped part 16 onto the part 24. The bore 26 of the ball-shaped part is for this purpose made slightly conical, widening towards the part 24, and the part 24 is made with a corresponding taper.

The end of the carrier part may lie in any plane with respect to the plane of the rings, according to the purpose for which the instrument 35 is to be used.

What I claim is:

A ligator comprising in combination a bar-shaped carrier member for the surgical filament and a non-circular handle part, the carrier member being bent over at the free end and having a channel in the bend, the handle part having a finger ring at the free end and carrying a sleeve-like member guided thereon, and a spring brake for the sleeve-like member, finger rings being secured on opposite sides to the said sleeve-like member, one of the said finger rings being movable for clamping the filament together with the fixed finger ring.

HANS ALBERT ROEDER. 50
